US0D1046135S

(12) **United States Design Patent** (10) **Patent No.:** **US D1,046,135 S**
(45) **Date of Patent:** **** Oct. 8, 2024**

(54) **SUTURE FASTENER**

(71) Applicant: **LSI Solutions, Inc.**, Victor, NY (US)

(72) Inventors: **Jude S. Sauer**, Pittsford, NY (US);
Jason C. Patti, Rochester, NY (US)

(73) Assignee: **LSI Solutions, Inc.**, Victor, NY (US)

(**) Term: **15 Years**

(21) Appl. No.: **29/855,251**

(22) Filed: **Sep. 30, 2022**

Related U.S. Application Data

(63) Continuation of application No. 16/741,873, filed on Jan. 14, 2020, now Pat. No. 11,484,302.
